UNITED STATES PATENT OFFICE.

ALFRED J. WARE, OF SEATTLE, WASHINGTON.

PRINTING-MACHINE.

1,014,986.

Specification of Letters Patent. Patented Jan. 16, 1912.

Application filed January 3, 1910. Serial No. 536,232.

To all whom it may concern:

Be it known that I, ALFRED J. WARE, a citizen of the United States, residing at Seattle, in the county of King and State of Washington, have invented certain new and useful Improvements in Printing-Machines, of which the following is a specification.

This invention relates to marking or printing machines; and has for its object 10 to provide an improved machine of this character which is particularly adapted for printing upon bank checks their face values in denominational words or symbols.

A machine embodying my invention consists in the employment of a series of wheels 15 having type characters upon their peripheries; devices whereby the wheels are individually rotated into predetermined printing positions; devices whereby the wheels 20 are automatically locked in such set condition; devices actuated through an agent whereby the type presented upon the printing-line has ink applied thereto and, upon the withdrawal of the inking appliances, 25 the continued action of such agent causes the article to be printed to be brought into printing relation with the inked type line, together with the subsequent releasing of the wheels from their locked condition; and 30 means for automatically restoring the wheels and the setting appliances therefor to normal inoperative positions.

The invention further consists in the novel construction and combination of parts 35 as will be hereinafter described and claimed.

In the accompanying drawings, Figure 1 is a side elevation of a printing machine constructed according to my invention, with a part of the frame removed and the containing case in section. Fig. 2 is a fragmentary plan view of the same. Fig. 3 is a plan view with a portion of the containing case broken away and certain parts of the mechanism omitted. Fig. 4 is a vertical section of a part of the machine taken through 4—4 of Fig. 1. Figs. 5 and 6 are side elevations of coöperating elements which relate respectively to the type-wheel brakes and to the inking mechanism.

50 Referring to the drawings, 10 designates the side members of the machine frame which is supported upon a suitable base 11.

Fixedly connected with said frame members and extending transversely therebetween is an arbor 12 upon which is mounted 55 for independent rotary movement a plurality of wheels 13 severally bearing series of type characters, such as the words "one", "two", etc., upon portions of their peripheries (indicated by 14 in Figs. 1 and 4) and 60 having other portions thereof provided with gear teeth 15. The latter are desirably formed of less width than the faces of the respective wheels. Mounted for rotation upon another transversely disposed arbor 17 65 which is also fixedly secured to said frame members is a plurality of toothed pinions 18 which mesh with the teeth 15 of the respective wheels. Each of these pinions is integrally connected, as by hubs 19, with 70 toothed wheels 20 which are respectively engaged by chains 21 which pass about sprocket wheels 22 located to the rear and about idlers 23, to the front of the machine. One of the links, as 21', of each 75 chain is formed with a block attachment 24 which is bored to accommodate a longitudinally arranged guide rod 25. These attachments are each provided with a handle 26 which extends upwardly through slots 80 27 provided in the top 28 of the machine casing. In proximity to the slots are columns of numbers 29 which are respectively spaced so that when a handle 26 is moved to be opposite a particular number of a column, the affected chain will actuate the associated sprocket wheel 20 and pinion 18 to impart motion to a type-wheel sufficient to present a corresponding type character there- 85 of in the printing line, or to the underside 90 of the wheels and in a vertical plane with the axis of the wheels.

For selectively positioning the type-wheels, pointers 26', as shown in Fig. 3, are provided upon said handles to designate the 95 corresponding number in the columns 29. Drums 30 having numbers or symbols, such as 30', upon their peripheries, are also provided to facilitate the proper movements of the type-wheels. The drums are respectively 100 connected by trains of gears with the aforescribed wheel-setting contrivances, so that the drums will be caused to expose numbers or symbols at a slot 31 provided in the cas-

ing top 28 which will be similar to the type set in the printing line. Such trains of gears may severally be comprised of a pinion 32 (Figs. 1 and 2) mounted upon an arbor 33 5 and integrally connected with a sprocket wheel 22, said pinion meshes with a gear 34 which likewise meshes with a gear 35 secured for rotation with one of the drums 30. 35' denotes the arbor for said drums 10 and the gears 35, and 36 is the arbor for the gears 34. Upon the last named arbor, and fixedly secured to the respective gears 34, are gears 37 in mesh with sector-gears 38 which are mounted for oscillation upon a 15 stationary shaft 39. A spring 40 is connected with each of the sector gears as shown in Fig. 1, and with a stationary rod 41. These springs tend to swing the respective sector gears rearwardly and, through the 20 medium of the associated trains of gears and sprocket-chains, effect the restoration of the type-wheels to their normal inoperative positions and a corresponding movement to each of the respective drums. In order, 25 however, to secure the type-wheels from being accidentally moved from set positions prior to an impression being had therefrom, brake devices are provided of sufficient power to withstand the counter force of the 30 springs 40 and yet be yieldable to the rotation of the wheels when being individually adjusted through the instrumentality of the respective handles 26. More particularly, the brake devices for each type-wheel com- 35 prises a lever 42 fulcrumed intermediately of its length to a stationary rod 43 which is located above the type wheels and somewhat to the rear of a plane projected vertically through the axis thereof. At the forward 40 end of each such lever is a roller 44 which is normally pressed against and into the interstices between the teeth of a type-wheel through the office of a compression spring 45 which is supported by a bar 46 of the ma- 45 chine frame and acting upwardly under the rearward arm of a lever. To the rear of the frame is journaled a shaft 47 which may be given partial rotary movements from a manually operable crank 48 provided exte- 50 riорily of the machine casing. Intermediate of the length of this shaft there is fixedly secured thereto a pair of elements 49 which are each provided to the forward side with an arc-shaped slot 49' to respectively accom- 55 modate pins 50. Each of these pins serve to connect the upper ends of the pairs of downwardly extending links 50' which have their lower ends connected by a rod 51 with the rear arms of spaced levers 52 which are ful- 60 crumed to a transverse shaft 53.

Secured to the shaft 47 is the end of a coil spring 54 whose other end is connected with the rod 51 and is designed to swing the elements 49 in the direction indicated by the 65 arrow in Fig. 5 so that the lower ends of the

slots 49' will normally bear against the pins to elevate the rear arms of levers 52. Adjacent to the rod 51, the levers 52 are connected by links 55 with a rod 55' carried by the rear arms of levers 56 which are fulcrumed to a 70 rod 56' fixedly secured to the frame. The other arms of levers 56 carry a rod 57 which serves as a fulcrum support for a plurality of upright levers 58, one for each of the 75 brake-levers 42. Each of the levers 58 is provided in its upper arm with a hook 58' at such a distance above the fulcrum rod 57 that when the rod 57 is in its lowermost position, the hooks will be somewhat below the 80 level of the upper surface of the rear arms of the brake-levers 42, as illustrated in Fig. 1.

The upper arms of levers 58 are of a length to be engageable by stud 21² provided upon the respective sprocket-chains 21. Said studs are located at a distance to the front of the respective block attachment 24 so that when the latter are moved rearwardly the studs will encounter the upper arms of levers 58 to effect the rearward tilting of the same against the action of springs 59 which connect the lower arms of the levers with the rod 55'.

It is to be noted that the upper arm of a lever 58, through its engaged condition with a stud, is held to be away from its respective brake-lever 42 when the block attachment 24 is in the position whereat the handle 26 is at the rear of its slot 27 in the casing. Such a position of a block attachment corresponds to a position of the affected type wheel whereat there is no denominating character presented in the printing line. Furthermore, when the levers 58 are thus caused to be inoperative, the brake levers are operative to lock the type-wheels against accidental movement. Supplementary means is afforded for collectively controlling the levers 58 so that they may be temporarily inoperative with respect to said brake levers. Such means comprises a rod 60, pivotally mounted in the machine frame and having an offset mid-portion 60' which, upon being swung into the position indicated by broken lines *a* in Fig. 1, by means of a finger-piece 60² (Figs. 2 and 3), will thrust such lever arms backwardly; but, normally, the offset portion of the rod would be pendant, as shown by full lines in Fig. 1, whereat it would have no influence upon the movements of the levers. Below the type wheels is a platen 61 of felt, or an equivalent, which is attached to a block 62 having depending bosses 63 (Fig. 4) which are slidably fitted for vertical movements in guide-sockets 64 provided in the frame-base. Yieldingly supported on springs 65 which are partially housed in recesses of the block 62 is a superposed plate 66 having an aperture to allow the platen being protruded therethrough when the 130

block is elevated as will be presently explained. To limit the upward movement of the plate 66 in relation to the block 62, I employ bolts 67, (Fig. 1) having heads which fit into counter sunk holes in the plate and extend through the block to receive adjustable nuts below the latter.

Above the plate 66 is a second plate 68 which is supported near each end from bolts 69 extending into holes provided in the respective frame members 10. These bolts are slotted or recessed, as at 69', to accommodate the points of screws 70, which serve to limit the downward travel of the plate which is thus urged by a spring 71 which acts against the top of each bolt.

Plate 68 is provided with an aperture 68' (Fig. 6) to afford space for a line of type upon the type wheels to pass through when the plate is elevated with the other plate to accomplish the printing of the type characters upon a check which is introduced between the two plates. The inking devices consist of an ink-pad, or strip of felt, 72, which is detachably secured as by screws 73 to a transverse member 74 of a substantially U-shaped pad carrier whose respective side members 75 are pivotally connected by pins 76 with controller members 77 which are mounted for oscillation upon the arbor 12 in proximity to the frame member 10. The referred to pivotal connections are located to the rear of the arbor. Below the arbor and to the forward side of each of the carrier members 75 is a laterally directed lug 75' which supports a spring 78 which is confined at its outer end by a collar 79 upon the outer end of a stem 80 which extends through a hole in the lug to be secured at its other end to the adjacent controller member. Said controller members are each provided with an upstanding arm 77' which is connected by a link 81 with an arm 82 mounted for oscillatory movement upon the shaft 47. Pivotally connected to each of the arms 82 is a detent 83 provided to the front of its connection with an arm with a lug 83' which is adapted to be engaged by a shoulder 84 of an adjacent disk 84' and thereby to the shaft 47, to which the disks are rigidly secured, in a reverse direction to that indicated by the arrow in Fig. 6. Each said detent is extended to the rear of its connection with an arm 82 to furnish an abutment 83² which, upon occasion, is arranged to be impinged by the point of an adjustable screw 85 carried by the respective link 81 to the rear of the latter's connection with the arms 82 for the purpose of tilting the detent out of engagement with the aforesaid disk-shoulder 84 and in opposition to springs 86 acting to maintain the respective detents in engagement at each side of the machine. 87 represents a spring 65 such as provided for each of the links 81 to

retract the links and cause the inking pad to be swung forwardly with the pad-carrier when the detents 83 are disengaged from the disks 84'. A stop, such as a pin 88, is secured in the frame members 10 at each side of the machine to arrest the rearward swing of the pad carrier when the latter is brought into a vertical position with the pad below the printing line.

It will be seen from the foregoing description that the wheels 13 which carry the type characters are individually set by moving the chains 21 through the medium of the attached handles 26 until the pointers 26 thereof are brought to indicate the selected numbers in the columns 29. When the wheels are thus set, the drums 30 for the several wheels are, by the intermediate trains of gears, correspondingly moved to expose, through the casing slot 31, symbols 35 corresponding to the type characters as they are successively assembled in the printing line. During these setting movements of the type wheels the sector gears 38 are caused by the respective trains of gears to 90 be swung forwardly in opposition to the springs 40. As each wheel is set it is locked against accidental displacement as well as the pull exerted by the springs 40.

The printing line being composed, the article to be printed is introduced between the plates 66 and 68. The crank handle 48 is now manipulated to actuate the shaft 47 to rock the latter in the direction contrary to that indicated by the arrow in Fig. 5, whereupon the disks 84' are rotated from the position in which illustrated in Fig. 1 to that shown in Fig. 6 resulting in the detents, which are engaged by the disks being swung forwardly and to transmit, through the medium of the links 81, a rocking movement to the controllers 77 which are accompanied by the ink-pad carrier until the side members 75 of the same encounter the pins 88, when continued movement of the controller will, through the pin connections 76 and the stop pins 88, cause a vertical movement to the carrier to effect the inking of the printing line of the type wheels. A further movement of the shaft 47 will affect the links 81 to cause the points of the screws 85 to bear against the respective detents 83² and thereby tilt the latter against springs 86 so that the detent is disengaged from the disks. The links 81 which are coupled with said detents being now released, the springs 87 assert themselves to restore the various parts of the inking mechanism to their normal positions in which they are represented in Fig. 1. Meanwhile the elements 49 have been swung with shaft 47 until when the ends of the slots 49' engage the pins 50 whereupon, and, by a still further movement of the shaft 47, the links 50' are influenced to operate the levers 52 which elevates the 130

block 62 to accomplish the printing of the article, and likewise effect, through the links 55 and levers 56, the raising of the levers 58, as will be understood from an inspection of 5 Fig. 5. The crank handle 48 is now released and the spring 54 acts to restore the shaft 47 into its original position resulting in the movement of the lever 52 which allows of the retraction of the block 62 for 10 the removal of the printed article, and the uplifting of the links 55 with a consequent downward movement of the levers 58 to bring the hooks 58' thereof into engagement with the brake-levers 42 and thereby disengage the brake-rollers 44 from the type wheels. The relative position now occupied by the parts just referred to are indicated by broken lines in Fig. 5.

When the brake rollers are thus disengaged the springs 40 serve to actuate the various trains of gears 37, 34, and 32 to make the respective sprocket wheels 22 operative to move the chains 21 so that the pinions 18 are actuated to rotate the type-wheels 13 into inoperative position and which will be consummated immediately following the studs 21² of the chains 21 striking the levers 58 and the dislodgment of the hooks 58' thereof from the brake levers 42 20 to permit the springs 45 to exercise their office of reengaging these brake-levers with the respective wheels. Should it be desired, however, to make a duplicate of a composed printing line of type-characters, then the 25 rod 60 is turned by the finger-piece 60² to revolubly move the offset portion 60' of the rod against the levers 58 so that the latter will be tilted rearwardly and so made, in their downward movement, incapable of engaging the brake-levers which would continue to act and the type-wheels remain undisturbed.

What I claim as my invention, is:—

1. In a printing machine, a plurality of 45 type wheels, springs serving to yieldingly maintain the respective wheels in inoperative position, chain actuated means for rotating said wheels into selected printing positions in opposition to the several springs, 50 means for securing said wheels in adjusted positions, a platen on which the article to be printed is supported, means for applying ink to the wheels, and a means for successively actuating the ink applying means, the 55 platen to effect the printing and the release of said wheel securing means whereby said springs are enabled to restore the wheels to their inoperative positions.

2. In a printing machine, a plurality of 60 type-wheels, springs serving to yieldingly maintain the respective wheels in inoperative position, chain actuated means for rotating said wheels into selected printing positions in opposition to the several springs, 65 means for securing said wheels in adjusted

positions, a platen on which the article to be printed is supported, means for applying ink to the wheels, a means for successively actuating the ink applying means, the platen to effect the printing and the release of said 70 wheel securing means whereby said springs are enabled to restore the wheels to their inoperative positions, and a series of drums operatively connected with said wheels whereby the setting of the wheels may be 75 determined from the relative positions of the drums.

3. In a printing machine, the combination with a stationary shaft, a series of type-wheels rotatably mounted upon said shaft, an automatic braking device for each wheel, 80 a platen on which the article to be marked is supported, an inking pad, an inking-pad carrier connected for limited oscillatory movements to said shaft, a controller for 85 said carrier mounted upon said shaft, a second shaft, a crank handle for operating the last named shaft, connections between this shaft and the platen, the brake devices, and said controller whereby the oscillatory 90 movements of such shaft causes the successive operations of the inking-device, the platen, and the disengagement of the brake devices.

4. In a machine for printing checks or 95 other articles, the combination with a stationary shaft, a series of type-wheels rotatably mounted upon said shaft, an automatic braking device for each wheel, a platen on which the article to be marked is 100 supported, an inking pad, an inking-pad carrier connected for oscillatory movements to said shaft, a controller for said carrier mounted upon the shaft, a second shaft, a crank handle for operating the last named 105 shaft, connections between this shaft and the platen, the brake devices, and controller whereby the oscillatory movements of such shaft causes the successive operations of the inking device, the platen, and, normally, the 110 disengagement of the brake devices, and a means whereby the last named shaft may be operated without affecting the brake devices.

5. In a machine for printing checks or 115 other articles, the combination with a stationary shaft, a series of type-wheels rotatably mounted upon said shaft, a spring for each wheel and tending to yieldingly retain the same in inoperative positions, 120 means for individually setting said wheels in opposition to the respective springs, an automatic braking device for each wheel, a platen on which the article to be marked is supported, an inking pad, an inking pad 125 carrier connected for limited oscillatory movements to said shaft, a controller for said carrier mounted upon the shaft, a second shaft, a crank handle for operating the last named shaft, connections between this 130

shaft and the platen, the brake devices, and controller whereby the oscillatory movements of such shaft causes the successive operations of the inking-device, the platen, and the disengagement of the brake devices, and a means whereby the aforesaid springs are rendered temporarily inoperative.

6. In a machine for printing checks or 10 other articles, the combination with a stationary shaft, a series of type-wheels rotatably mounted upon said shaft, a spring for each wheel and tending to yieldingly retain the same in inoperative positions, 15 means for individually setting said wheels in opposition to the respective springs, an automatic braking device for each wheel, a platen on which the article to be marked is supported, an inking pad, an inking pad 20 carrier connected for limited oscillatory movements to said shaft, a controller for said carrier mounted upon the shaft, a second shaft, a crank handle for operating the last named shaft, connections between this 25 shaft and the platen, the brake devices, and said controller whereby the oscillatory movements of such shaft causes the successive operations of the inking device, the platen, and the disengagement of the brake devices, and 30 a means whereby the last named shaft may

be operated without affecting the brake devices and whereby the aforesaid springs are rendered temporarily inoperative.

7. In a machine of the class described, a series of type-wheels, devices for individually setting said type wheels into predetermined printing positions, a spring for each of the wheels and acting to restore the wheels from their set positions to inoperative positions, a brake device for each wheel, a spring 35 for effecting the engagement of each of the brake devices, a platen on which the article to be marked is supported, a means for operating the platen to move said article into printing relation with the type-wheels, a 40 spring for retracting the platen from the type-wheels when said means are inoperative, mechanical connections between said means and the various brake-devices for causing the latter to be disengaged when the 45 platen is being retracted, and means made operable by the first mentioned springs and the type-wheel setting-devices whereby said mechanical-connections are made inoperative to allow the brake-devices to reengage 50 the type-wheels.

ALFRED J. WARE.
